US0D1053477S

(12) **United States Design Patent** (10) **Patent No.:** **US D1,053,477 S**
Li (45) **Date of Patent:** **** Dec. 3, 2024**

(54) **REMOTE CONTROLLED DOG TRAINING DEVICE PAIR**

(71) Applicant: **Shenzhen city Liaona Technology Co. Ltd.**, Shenzhen (CN)

(72) Inventor: **Lanxin Li**, Shenzhen (CN)

(73) Assignee: **Shenzhen city Liaona Technology Co. Ltd.**

(**) Term: **15 Years**

(21) Appl. No.: **29/861,126**

(22) Filed: **Nov. 28, 2022**

(51) LOC (14) Cl. **30-99**

(52) U.S. Cl.

USPC **D30/199**

(58) **Field of Classification Search**

USPC D10/78, 80, 104.1; D13/168, 154; D14/137, 217, 218; D30/144, 151, 152, D30/160, 199

CPC A01K 27/00; A01K 27/001; A01K 27/006; A01K 27/009; A01K 15/021; A01K 15/022; A01K 15/023

See application file for complete search history.

(57) **CLAIM**

The ornamental design for a remote controlled dog training device pair, as shown and described.

DESCRIPTION

FIG. 1 is a first perspective view of a remote controlled dog training device pair showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof; and,

FIG. 8 is a bottom view thereof.

The broken lines shown in the drawings depict portions of the remote controlled dog training device pair that form no part of the claimed design.

1 Claim, 8 Drawing Sheets
